CLAIM

The ornamental design for a module for a measuring instrument, as shown and described.

DESCRIPTION

FIG. 1 is a perspective view of a module for a measuring instrument showing my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a bottom view thereof;
FIG. 8 is a perspective view of another embodiment of the module for a measuring instrument;
FIG. 9 is another perspective view thereof;
FIG. 10 is a front view thereof;
FIG. 11 is a rear view thereof;
FIG. 12 is a left side view thereof;
FIG. 13 is a right side view thereof; and,
FIG. 14 is a bottom view thereof.

The broken lines are for the purpose of illustrating portions of the module for a measuring instrument and form no part of the claimed design.
